CLAIM

An ornamental design for a filter box lid as shown and described.

DESCRIPTION

FIG. 1 is a first top perspective view of a filter box lid, in accordance with an embodiment;

FIG. 2 is a second top perspective view of the filter box lid of FIG. 1;

FIG. 3 is a third top perspective view of the filter box lid of FIG. 1;

FIG. 4 is a first bottom perspective view of the filter box lid of FIG. 1;

FIG. 5 is a second bottom perspective view of the filter box lid of FIG. 1;

FIG. 6 is a third bottom perspective view of the filter box lid of FIG. 1;

FIG. 7 is a fourth bottom perspective view of the filter box lid of FIG. 1;

FIG. 8 is a top view of the filter box lid of FIG. 1;

FIG. 9 is a bottom view of the filter box lid of FIG. 1;

FIG. 10 is a rear view of the filter box lid of FIG. 1;

FIG. 11 is a front view of the filter box lid of FIG. 1;

FIG. 12 is a left side view of the filter box lid of FIG. 1; and, FIG. 13 is a right side view of the filter box lid of FIG. 1.
